UNITED STATES PATENT OFFICE.

WILLIAM M. BARNARD, OF SPRINGFIELD, MASSACHUSETTS.

SASH-WEIGHT-CORE-FORMING DEVICE.

Application filed April 14, 1922. Serial No. 552,575.

To all whom it may concern:

Be it known that WILLIAM M. BARNARD, a citizen of the United States of America, residing at Springfield, in the county of ⁶⁰ Hampden and State of Massachusetts, has invented certain new and useful Improvements in Sash-Weight-Core-Forming Devices, of which the following is a specification.

10 This invention relates to improvements in devices for making cores for use in casting sash weights and its leading object is to provide a device of extreme simplicity which will enable the worker to make a **15** large number of cores and will imprint the weight number on the core, to leave such imprint on the cast sash weight near the eye thereof.

With the above and other objects in view **20** the invention consists in certain new and useful constructions, combinations and arrangements of parts, clearly described in the following specification and fully illustrated in the accompanying drawings, in which:

25 Fig. 1 is a vertical sectional view through a core box, showing the device in side elevation.

Fig. 2 is an end view of the device.

Fig. 3 is a transverse sectional view **30** thereof.

Fig. 4 is a plan view of a modified form.

Fig. 5 is a transverse sectional view thereof, taken on line A of Fig. 4.

Referring to the accompanying drawings **35** illustrating the practical application of the invention 5 designates a core box, which include the base 6, the cylindrical wall 7 and the tapered stem 8, which is designed to have a non-rotative fit in the socket or hole **40** of the table or work bench, not shown.

The opposing sides ^{7a} and ^{7b} of the wall 7 are formed with openings ^{7a'} and ^{7b'}, which are disposed in registration. The upper and inner face of the base 6 is formed **45** with a taper so as to shape the end of the core accordingly. The upper end of the core box is normally open to admit by hand filling the sand to be used.

A device 11 is adapted to be extended **50** through the openings ^{7a'} and ^{7b'}, and this device consists of a pair of companion jaws 12 and 13. The lower jaw member 13 is formed with a longitudinal trough ^{13a} and a handle 14 extending therefrom, which is **55** formed with a terminal eye 15. The upper jaw member 12 is formed with a longitu-

dinal trough or pocket ^{12a} which is adapted to receive the jaw 12, and on the upper face of the central wall of the jaw member 12 a character 16 is soldered or otherwise secured in place. The upper jaw member 12 is also formed with a terminal lip 17 on its forward end and a terminal eye 18 on its rear end, which is pivotally connected to the eye 15 by means of the pintle 19. The eye ⁶⁵ 18 is formed on the handle extension 20 of the upper jaw 12. A stop 21 is formed on the lower jaw eye which is adapted to be engaged by the shoulder 22 formed on the eye of the upper jaw member. A stop 23 ⁷⁰ is also formed on one of the members 13 to limit the insertion of the device in the core box, so that the character will come in a central or axial position therein.

The upper jaw is automatically elevated ⁷⁵ on the lower jaw by means of a spring 24, which is enclosed in the chamber provided by the trough of the lower jaw and the pocket of the upper jaw, the spring being anchored at its upper end to the eye ^{24a} ⁸⁰ formed on the jaw 13 and bearing at its lower end against the jaw 12.

The device is inserted in the core box, with the upper jaw depressed by hand pressure, so that the character will not strike against ⁸⁵ the wall of the core box. When the device is fully inserted the pressure is withdrawn and the jaws will be forced apart, so that the upper jaw will be forced into forming position. The core box is then filled with ⁹⁰ sand and after this is packed into place by slight hand pressure, which is insufficient to close the jaws on each other, the upper jaw is forced downwardly, so that the character is withdrawn from contact with the sand, ⁹⁵ and the device is then withdrawn from the core box.

In Figs. 4 and 5 I show a device for use in connection with two core boxes. This device includes the upper jaw members ¹⁰⁰ 30 and 31 which are pivoted to the low jaw members ^{30a} and ^{31a} as in the construction shown in Fig. 1. The lower jaw members are connected to each other by integral and rigid bars 32 and 33. The bar 33 carries the bearing lugs 34 and 35, and the lever 38 is pivoted by its shaft 36 on these lugs. This lever carries on its lower end a cam ¹⁰⁵ 37, which is designed to work against the cross rod ^{38a}, the ends of which engage the spring pressed upper jaws 30 and 31. By swinging the lever the two upper jaws will

be simultaneously depressed, and the forward ends of the two formers can be inserted in the core boxes 5, and withdrawn.

I claim:

- 5 1. A sash weight core forming device consisting of pair of members, one having a longitudinal channel, one of the members having sliding engagement with said channel, a spring carried and disposed in said
- 10 longitudinal channel and bearing against the other member tending to separate said members, each member being provided with longitudinal handle, the rear ends of the handles being pivotally connected to each
- 15 other, one of said members having a character thereon for imprinting the sand from

which the sash is molded, the two members being so arranged that upon manual pressure of one end upon any portion of the handles the character will be moved inwardly to the sand and the device may be slidably withdrawn.

2. A pair of weight forming devices, each including relatively movable jaws one of which carries a character, means connecting the devices in spaced relation, a cross bar bearing on certain of the jaws for moving the same against the opposite jaws, and a lever for moving the cross bar to close the jaws.

Signed by me at Springfield, Mass.

WILLIAM M. BARNARD.
